CLAIM

The ornamental design for an 8-amp battery as shown and described.

DESCRIPTION

FIG. 1 is a top perspective view of an 8-amp battery;
FIG. 2 is first end view thereof;
FIG. 3 is a second end view with connection port thereof;
FIG. 4 is a first side view thereof;
FIG. 5 is a second side view thereof;
FIG. 6 is a top plan view thereof; and,
FIG. 7 is a bottom plan view thereof.

The broken line showing of various surface features is included for the purpose of illustrating portions of the 8-amp battery and form no part of the claimed design.

1 Claim, 7 Drawing Sheets
